UNITED STATES PATENT OFFICE.

PHILANDER PERRY, OF WATERFORD, ASSIGNOR TO HIMSELF AND EPHRAIM H. BENDER, OF ALBANY, NEW YORK.

IMPROVEMENT IN WIPERS FOR BLACKBOARDS.

Specification forming part of Letters Patent No. 36,589, dated September 30, 1862.

To all whom it may concern:

Be it known that I, PHILANDER PERRY, of Waterford, Saratoga county, State of New York, have invented a new and useful article of school stationary for the purpose of a slate and blackboard wiper; and I declare the following specification, with the drawings connected therewith as a part of the same, to be a full and perfect description of my invention.

Figure 1 represents the article as prepared for a blackboard-wiper, and Fig. 2 for a slate-wiper.

In Fig. 1 a portion of the covering is shown as removed to exhibit the filling material.

A is an oblong piece of wood, like a clothes-brush handle, of convenient size for handling, say eight inches long, three and a half wide, and one inch thick. This is to be covered by a piece of canton-flannel, (cotton) B, or like material, secured to it by nailing along the edges at C, or any other convenient mode of attaching it, leaving a space for a stuffing or filling, S, between the wood and cover of about three-quarters of an inch or an inch. This stuffing or filling is composed of wood shavings crushed by manipulation, so as to form a friable mass of some elasticity, together with clippings of woolen cloth, and for certain purposes with small bits of sponge. The proportions of these materials may be about equal quantities of shavings and cloth mixed together. The sponge, which is to be put in whenever the rubber is to be wetted, and not used exclusively as a dry rubber, is to be scattered over the surface of the other filling and next to the cloth covering, so as to hold the moisture near the surface.

The small or slate wiper, Fig. 2, is made of a central piece of board at D, the covering passing around it, so as to form a sack above and below it at E E, the one side to be filled with shavings and cloth described, the other with cloth and sponge, this latter to be moistened to wash the slate and the other to be used as a drier.

Blackboard-rubbers now in use are simply oblong blocks covered with sheepskin, the

wool outside, or with buckskin. This leather covering soon becomes charged with chalk-dust, so that after a short time of use instead of fairly cleaning the board it simply covers it with a gray coat, upon which writing becomes both difficult and illegible. Besides, the covering operating, as it does, between two unyielding surfaces, nothing but a leathery substance would last any time for a rubber, and even that wears rapidly out, requiring frequent covering to the blocks. The filling-in employed within my rubbers by its elasticity relieves the pressure and reduces the abrasion, permitting the use of cloth covering, which is a cheaper and better article. Further, the cloth (cotton) covering, from its peculiar texture, carries off the particles of chalk from the board or slate, instead of grinding it down upon the surface, as does leather. It also allows the use of moisture to clean the board or slate.

Moisture soon rots leather covering, being long retained by it, and not evaporating readily from its pores as from cloth, an important advantage in favor of cloth. I therefore allege that I produce a more durable, serviceable, and effective wiper than has ever yet been made, and one that, from the cheapness of its material and construction, meets the wants of common schools as a part of its economical apparatus, and is within the reach of all common-school pupils.

What I claim as my invention, and desire to secure by Letters Patent as a new article of manufacture, is—

The combination of the wooden blocks A and D with a covering of cloth, the space between them being filled with a stuffing composed of prepared shavings and clippings of cloth, with or without pieces of sponge, substantially as described, and for the purposes set forth in the within specification.

PHILANDER PERRY.
